UNITED STATES PATENT OFFICE

GEORGE INNES, OF DAVENPORT, IOWA, ASSIGNOR TO INNES MANUFACTURING COMPANY, OF BETTENDORF, IOWA, A CORPORATION OF DELAWARE

GRAIN-SHOCKING MECHANISM

Application filed June 17, 1926. Serial No. 116,543.

This invention relates to machines for shocking grain received from a binder and particularly to mechanism for automatically conveying grain from a binder to a shocker basket and for recovering grain particles. 5

In this specification and in the appended claims the term "grain stalks" will refer to stalks having heads attached thereto and "grain particles" will refer to individual 10 grains or heads of grain or parts thereof unattached to stalks or having but very short stalks attached thereto.

In the past, while various methods and means have been employed for transferring 15 bundles of grain from a binder to a shocker basket, loose grain stalks and grain particles accumulating in the binder and upon the binder deck have been ordinarily unrecovered, resulting in a very appreciable economic 20 loss. Furthermore, any grain particles loosened from the grain bundles during the conveyance thereof from the binder deck to the shocker basket have ordinarily been lost.

An object of my invention is to provide an 25 advantageous and compact mechanism for conveying bundles of grain and grain stalks from a binder to a shocker basket.

Another object of this invention is to provide means for recovering grain particles 30 from a binder, and disposing such particles in a suitable container.

A further object of the invention is to provide means for receiving grain bundles, grain stalks and particles from a binder deck, delivering 35 said bundles and stalks to a shocker basket, and collecting said grain particles and disposing them in a suitable container.

Another object of this invention is to provide suitable mechanism for receiving grain 40 bundles from a binder with the butt ends of said bundles facing forwardly, reversing the position of said bundles and delivering them to a shocker basket.

In the drawings:

45 Figure 1 is a perspective view of a mechanism according to my invention disposed in cooperative relation with and forming an integral part of a grain shocker, parts being broken away to show the interior of the mechanism;

Fig. 2 is an elevation from the left side of a mechanism according to my invention attached to a grain shocker;

Fig. 3 is a top plan view of the structure shown in Fig. 2;

Fig. 4 is a diagrammatic top plan view showing a binder deck, a grain shocker basket, and mechanism according to my invention disposed intermediate said binder and shocker basket;

Fig. 5 is an elevation on line 5—5 of Fig. 4;

Fig. 6 is an enlarged fragmentary elevation from the left side, partly broken away of the mechanism shown in Fig. 2;

Fig. 7 is an enlarged fragmentary elevation, partly in section, of gear mechanism shown in Fig. 6;

Fig. 8 is a horizontal section on line 8—8 of Fig. 7;

Fig. 9 is a section on line 9—9 of Fig. 6; and

Figs. 10 to 13, inclusive, are diagrammatic elevations showing the path of grain through the mechanism of my invention.

While the grain shocker illustrated in the drawings is substantially similar in general characteristics to that shown in my U. S. Patent No. 1,512,768, dated Oct. 21, 1924, it will be understood that the mechanism of my present invention may be employed with or made an integral part of various types and forms of shockers.

My improved mechanism, which may be termed a "grain saver", has several functions, including those which will now be mentioned. The grain saver receives from the binder deck not only the assembled grain in the form of bundles, but also grain particles and grain stalks. Due to the usual construction of binders, the grain saver receives the bundles with the butts thereof facing forwardly of the direction of movement of the harvesting machinery. The grain saver reverses the position of the bundles and delivers them adjacent the shocker basket with the butt ends facing rearwardly. Grain stalks are also delivered adjacent the shocker basket to form a part of the shock. Grain particles received from the binder deck, as well as particles loos-

ened from the bundles, are collected in a grain-tight receptacle and conveyed to a suitable container, which, for convenience, may be replaceable. The grain saver may be attached to a shocker or may form an integral part thereof.

The advantageous location of the grain saver with respect to the remainder of the harvesting machinery is illustrated diagrammatically in Figs. 4 and 5, wherein the grain saver 1 is shown as being disposed intermediate the binder deck 2 of the binder 3 and the shocker basket 4 of the shocker 5. Draft bar mechanism 6 is shown of a form adapted for use where the harvesting machinery is to be drawn by horses. When in operation, the machinery shown in Fig. 4 moves in a direction from right to left. It will be noted that the binder deck 2 is located adjacent the grain saver. Between the binder deck and the receptacle 9 of the grain saver is a trough 2a to receive the grain particles and stalks which are ordinarily lost in the field and hold them to be swept into the receptacle 9 by the transfer of the bundles from the binder deck. The trough 2a is secured to the grain saver mechanism by any suitable supporting means and is provided with a suitable slot 2b, through which the binder needle (not shown) operates, as is well understood. Preferably, at the side 2c and the under edge 2d of the slot is provided an upstanding flange to prevent loose grain particles from falling through the slot to the ground. The grain particles are directed around the slot and collect in the lower end of the trough and are swept with the bundles into the receptacle 9. It will be seen that the loose stalks which are out of line to come under the binding twine as the bundle is being bound will also be collected in this trough and swept, together with the grain particles, into the receptacle 9. It will also be noted that the construction of the trough 2a is such that on ejection, grain bundles and particles will be elevated sufficiently to be transferred to the grain saver regardless of differences in elevation between the trough 2a and platform 38 such as due to unevenness of the field surface. Grain bundles 7 are ordinarily transferred from the binder deck to the grain saver 1 in the position shown in Figs. 1 and 10, by the ejector fingers 8, (Figs. 4 and 5) which rotate about the shaft 8a as an axis. It will be understood, of course, that the bundles 7 may be transferred to the grain saver 1 by any suitable or equivalent means.

The grain saver 1 is shown as comprising a grain-tight metal receptacle 9 supported by the frame 10 of the shocker 5 and by additional strengthening members 11. The receptacle 9 is provided with an upwardly extending portion 12. In Figure 1 is shown a slightly modified form of grain saver, which will be described hereinafter.

Disposed within the receptacle 9 are the conveyor belts A, B, C, D and E, whereby the grain bundles 7 are reversed and grain stalks and bundles conveyed to the platform 13 and whereby grain particles are delivered to containers 14. The said conveyor belts rotate in the directions indicated in Figs. 10 to 13.

The receptacle 9 is shown as provided with side walls 15 and 16, end walls 17 and bottom 18. The upwardly extending portion 12 is provided with side walls 19 and 20 and bottom 21.

The belt A moves over rollers 22 and 23, which, in turn, are mounted on the axial rods 24 and 25 and locked against rotative movement with said rods. The rods 24 and 25 are journaled in suitable bearing members 26 and 27 (Fig. 2) affixed to the side walls 15 and 16. The belt A is preferably of canvas provided with wooden cleats 28, which cleats cooperate with the grain to convey the same.

Conveyor belt B is mounted on and moved by three rollers 29, 30 and 31, (Figs. 10 to 13) which, in turn, are carried by the axial rods 32, 33 and 34 journaled in the bearing members 35, 36 and 37 mounted on the side walls 15 and 16. The belt B is also provided with wooden cleats 28. Disposed over the top surface of the belt B is an apron 38, which is adjustable by the adjusting means designated at 39 to dispose the apron at the desired angle. The apron 38 is adapted to receive and support the bundles 7 received from the binder and direct such bundles into the interior of the receptacle 9.

The belt C is mounted on and rotates on rollers 40 and 41, which rollers are, in turn, mounted on the rods 42 and 43, journaled in bearing portions 44 and 45 attached to the side walls 15 and 16 of the receptacle 9. Between the rods 42 and 43 are a pair of guides 46, which are preferably made of wood, and which serve to keep the upper surface of the belt C in the desired plane. The belt C is provided with wooden cleats 28 similar to those on the belts A and B. Disposed between the upper and lower surfaces of the belt C is a conveyor mechanism 47, (Fig. 3) which preferably comprises a spiral screw conveyor to convey the accumulated waste material or chaff, which may collect between the surfaces of the belt, out of the machine and prevent clogging up of the conveyor mechanism. The said screw conveyor may be actuated by suitable gearing from the rod 42.

Conveyor belt D moves on rollers 51 and 52, which in turn, are mounted on the rods 53 and 54. The rods 53 are shown as journaled in the bearing members 45. The rods 54 are journaled in the bearing members 55. A pair of guides 56 is disposed between the rods 53 and 54 and serves to guide the upper

surface of the conveyor belt D. The oppositely disposed guides 56 may be connected and spaced from each other by suitable members 57, comprising, in the present case, nuts and bolts. The canvas belt D is provided with undercut wooden cleats 58 so arranged that grain particles may be readily carried up the incline.

Conveyor belt E moves on rollers 59 and 60, which, in turn, are mounted on the axially disposed rods 61 and 62. Rods 62 are journaled in the bearing members 63, which are movable toward and away from the belt D in the slots 64 of the U-shaped member 65, which surrounds the receptacle portion 12 and extends outwardly therefrom. The rod 61 is journaled at its ends in the gear casings 66, which are pivotally mounted on extensions of rod 34 as an axis, as will most clearly be seen by reference to Figs. 7 and 8. By the above-described mounting of the rods 61 and 62, it will be seen that the conveyor belt E may be moved toward or away from the conveyor belt D to permit bundles of grain of various dimensions to pass therebetween. Mounted between the rods 61 and 62 are a pair of guides 67, which serve to keep the surfaces of the conveyor belt E, and particularly the lower surface thereof, in desired position. The guides 67 may be maintained in spaced relation by means 57 similar to those employed with the guides 56 between the surfaces of the belt D. The belt E is provided with wooden cleats 28, similar to those previously described in connection with belts A, B and C. Outwardly of the guides 67 are provided a pair of sheet metal members 68, which are adapted to overlie the corresponding side walls 19 and 20 of the receptacle portion 12 so that said receptacle portion may be enclosed regardless of the position of the belt E with respect to the belt D. Tension springs 69 connected to the respective guides 56 and 67 serve to maintain the belts D and E in relatively close relation to each other until spread further apart by bundles of grain 7 moving upwardly therebetween, as will be later further described.

The power for driving the various belt conveyors described in the preceding paragraphs is obtained from the rotating axle of the moving shocker. Disposed on the axle 70 of the shocker is a gear wheel 71 cooperatively associated with a second gear wheel 72 mounted on the same shaft 73 as the sprocket wheel 74. The shaft 73 is suitably supported by bearing portions attached to the frame 10. Associated with the sprocket wheel 74 is the chain 75, by means of which power is transmitted to drive all of the belts. The chain 75 is shown as associated with sprockets located on the left-hand side of the machine. Thus, referring particularly to Figs. 2 and 6, there is disposed on the out-

er end of rod 54 a sprocket wheel 76, by means of which the belt D is driven.

On the shaft 77 (Fig. 8), journaled in the housing 66, is a sprocket wheel 78, which serves to drive belts B and E. On the same shaft 77 is mounted a gear wheel 78a, which, in turn, drives the gear wheels 79 and 80, (Fig. 7), which are respectively mounted on the rods 34 and 61. As previously mentioned, the housing 66 is pivotally mounted on the shaft 34, whereby a driving connection may be maintained with belts B and E, regardless of the position of the belt E with respect to the belt D. On the outer end of the rod or shaft 43 is the sprocket 81, by means of which the belt C is driven. Also supported on the shafts 77 and 43 are the links 82 and 83 (Fig. 6), which links are associated through a shaft supporting the chain-tightener sprocket wheel 84. The chain 75 thus passes over sprockets 74, 81, 84, 78 and 52, whereby the belts B, C, D and E are driven in the directions indicated in Figs. 10 to 13.

Referring to Fig. 2, on the right-hand end of the shaft 43 is a sprocket 85, and on the right-hand ends of shafts 24 and 42 are the sprockets 86 and 87, respectively. Pivotally supported from the rod 42 is an idler sprocket 88. A chain 89 passes over the above four sprockets, whereby the belt A is driven in a direction indicated in Fig. 10.

Extending upwardly from the side wall 16 and supported by member 90 is a deflector 91, which assists in directing bundles of grain 7 into the receptacle 9. Extending upwardly from the platform 13 at the left-hand side of the grain saver and connected to the side wall 19 is an upstanding guide member 92, which assists in directing grain bundles toward the shocker basket. For the same purpose, an upper guide member 93 is attached to the side wall members 68. Between the upper end of the belt E and the platform 13 (Fig. 3) is a screen 94, which is shown as comprising a series of parallel bars. The object of the screen is to permit grain particles to pass therethrough while bundles and stalks are carried thereover. Beneath the screen 94 and attached to the upper receptacle portion 12 is a hopper 95, which is open at the bottom. Adjacent the bottom of the hopper are hooks 96, to which the tops of the containers 14 may be attached. These containers are preferably grain sacks. Disposed on the frame 10 is a container support 97, which is adapted to support the bottom of a removable container 14 (Figs. 10 to 13).

The operation of my improved device is as follows:

Grain bundles 7 are transmitted by the ejector fingers 8 from the binder deck across the trough 2a, together with the loose grain particles and stalks, into the receptacle 9, the apron 38 and the member 91 assisting in di-

recting the bundles and material into the receptacle.

Referring now to Fig. 10, the conveyor belt A moving in the direction indicated in the drawing, moves the butt end of the bundle downwardly to the position shown in Fig. 11, at which time the conveyor C, together with the conveyor A, moves the bundle into the position shown in Fig. 12, from which position the conveyors D and E carry the bundles up the steep incline in a manner shown in Fig. 13 and deliver the bundle to the position shown in the dotted lines in Fig. 13, from which position on the platform 13 the bundles may be directed, manually or otherwise, into the shocker basket 4. It will be noted that any stalks will be likewise conveyed to the platform 13. It will be seen that by reason of the yieldable construction of the belt E, the said belt is movable to engage, together with the belt D, grain bundles 7 of varying degrees of thickness. It will be understood that the incline of the conveyors D and E is sufficiently steep that a pair of conveyors D and E engaging the bundles 7 on opposite sides thereof is desirable in order to convey the bundles up such steep incline, the yielding construction of the conveyor E permitting the conveyance of bundles of varying thickness. Grain particles entering the receptacle 9, on the other hand, are conveyed by the conveyors upwardly of the container D through the screen 94 and hopper 95 into a removable container 14.

It will thus be seen that I have provided a very convenient and efficient automatic mechanism for conveying bundles of grain from a binder deck to a shocker basket, and for recovering all of the loose grain particles and stalks from the binder deck.

It will also be seen that I have provided means for conveying recovered grain particles to a suitable replaceable container.

Furthermore, it is to be understood that the particular forms of apparatus shown and described, and the particular procedure set forth, and presented for purposes of explanation and illustration and that various modifications of said apparatus and procedure can be made without departing from my invention as defined in the appended claims.

What I claim is:

1. In binding and shocking apparatus, in combination, a trough arranged to receive grain bundles from a binder, an open-top grain-receiving receptacle, means for transferring said bundles from said trough to said receptacle, means within said receptacle to reverse the position of grain bundles in a vertical plane, and conveying means arranged to carry the reversed bundles upwardly to the top of a shocker basket.

2. In binding and shocking apparatus, in combination, a trough arranged to receive grain particles and bundles from a binder, an

open-top grain-tight grain receiving receptacle, means within said receptacle to reverse the position of grain-bundles in a vertical plane, conveying means arranged to carry the reversed bundles upwardly to the top of a shocker basket, and means for transferring said grain particles to a container.

3. In grain shocking apparatus, in combination, an open-top, grain receiving receptacle, means within said receptacle to reverse the position of grain bundles in a vertical plane, and conveying means arranged to carry the reversed bundles upwardly to the top of a shocker basket.

4. In grain shocking apparatus, in combination, an open-top grain-tight receptacle formed to receive grain bundles and grain particles, means within said receptacle to reverse the position of grain bundles in a vertical plane, conveying means arranged to carry the reversed bundles upwardly to the top of a shocker basket, and means for transferring said grain particles to a container.

5. In grain shocking apparatus, in combination, a grain-tight metal receptacle adapted to receive grain bundles from a binder with the butts of said bundles foremost, means within said receptacle to dispose said bundles of grain on the bottom thereof with the butts facing rearwardly, an inclined conveyor adapted to receive said bundles from the bottom of said receptacle and discharge said bundles to the shocker basket, and means to deliver said bundles from the bottom of said receptacle to said inclined conveyor.

6. In grain shocking apparatus, a bundle turning and conveying mechanism comprising a grain-tight receptacle having an inclined apron disposed to receive a grain bundle from a binder with the butt of said bundle facing forwardly, and conveyors carried by said receptacle to cause the bundle to be turned end for end and presented to a pair of upwardly inclined belt conveyors to convey the bundle to the top of the shocker basket.

7. In a grain shocking apparatus adapted to receive grain from a binder and transmit said grain to a shocker basket, in combination, an open-top grain-tight metal receptacle adapted to receive bundles of grain with the butts foremost, means disposed at one side of the container to direct the bundles from the deck of a binder into said receptacle, means adapted to turn said bundles end for end in said receptacle with the butts facing rearwardly, and an inclined conveyor adapted to convey said bundles to said shocker basket, and means to deliver said bundles of grain to said inclined conveyor.

8. In combination with a grain shocking apparatus including a shocker basket and a suitable receiving and conveying mechanism to receive the grain from the deck of the binder and transfer it to the shocker basket,

said mechanism including a grain-tight receptacle, a deflector to deflect successive bundles of grain ejected from the binder deck into the receptacle, mechanism in the receptacle to reverse the bundles of grain so that the butts face rearwardly, and conveyor mechanism to convey the bundles up a relatively steep incline to the top of the shocker basket, said conveyor mechanism having a 10 pair of opposed conveyors mounted to yieldingly engage bundles of variable thickness.

9. In grain shocking apparatus, a bundle turning and conveying mechanism comprising a grain-tight receptacle having an inclined receiving pan to receive bundles from the deck of a binder and having mechanism to turn the bundles end for end, and an upwardly inclined conveyor mechanism carried by said receptacle, said conveyor mechanism 15 comprising separately driven belt conveyors, the rolls of one conveyor being mounted for movement transversely relative to the other conveyor to engage bundles of variable thickness.

35 10. The invention specified in claim 8, in which the conveyors are each mounted to be separately driven about the conveyor rolls, the rolls of one conveyor being yieldingly mounted for transverse movement with respect to the other conveyor so that bundles of 30 variable thickness will be tightly engaged and readily conveyed to the shocker basket.

11. In a grain-tight attachment for a binder and shocker adapted to convey grain 35 ejected from the binder deck to the shocker basket, in combination, a grain-tight receptacle having an open-top sufficiently large to receive a bundle of grain vertically, a shield member extending upwardly on the side of 40 said open-top opposite to the binder adapted to direct bundles of grain toward said opening, an inclined apron disposed on one side of said opening adjacent to said shield member, a belt conveyor disposed in part under 45 said apron extending beyond said apron toward said opening and rotating in a direction toward said opening, a second conveyor disposed adjacent said shield member on the opposite side of said top opening from said first 50 conveyor adapted to rotate downwardly of said opening, a third belt conveyor disposed on the bottom of said receptacle and rotating in a direction away from said second conveyor, whereby said bundle of grain is caused 55 to travel along said third conveyor longitudinally in a reversed position, and a pair of inclined belt conveyors adapted to receive said bundles from said third conveyor and convey said bundles upwardly to the top of said 60 shocker basket.

12. In a grain-tight conveying attachment for a binder and shocker adapted to receive grain ejected from the binder deck and convey it to the shocker basket, in combination, a 65 substantially vertical member against which

a bundle of grain strikes on ejection from the binder deck, said member being adapted to direct said bundle into the open top of said conveying attachment, an inclined apron, a first belt conveyor disposed in part beneath 70 said apron, a second belt conveyor disposed on the opposite side of said top opening, said first and second conveyors moving in a direction downwardly of said opening, a cleated belt conveyor disposed at the bottom of said aperture, and a pair of inclined conveyors adapted to convey said bundle in reversed position to the top of said shocker basket, the upper of said inclined conveyors being yieldable dependent on the size of the bundle being conveyed. 75

13. In combination with grain shocking apparatus, a grain shocking machine including a shocker basket, and a suitable receiving and conveying mechanism to receive 80 grain bundles from the deck of a binder and to transfer said bundles to the shocker basket, said mechanism including a suitable grain-tight receptacle and conveyors arranged therein to reverse the position of said 85 bundles and convey them with the butts thereof facing rearwardly to the shocker basket, and means for collecting in a suitable container grain particles received from the binder deck and loosened within the conveying apparatus. 90

14. In grain shocking apparatus, in combination, a grain shocking machine including a shocker basket, and mechanism arranged between the deck of a binder and the 100 shocker basket, said mechanism including a grain-tight metal receptacle, an upright member disposed to receive the bundles of grain and grain particles ejected from the binder deck and to deflect said bundles and particles into said receptacle, conveying mechanism carried by the receptacle and adapted to convey the bundles to the shocker basket, means for separating the loose grain particles from the bundles, and means for collecting such grain particles in a suitable 105 container. 110

15. In grain shocking apparatus, adapted to receive bundles of grain from a binder with the butts thereof facing forwardly and to convey said bundles to a shocker basket with the butts facing rearwardly, in combination, a grain-tight metal receptacle adapted to receive bundles of grain and grain particles from a binder deck with the butts of said 115 bundles facing forwardly, mechanism within said receptacle to reverse the longitudinal position of said bundles, conveying means adapted to convey said bundles from the bottom of said receptacle to the top of said shocker basket with the butts of said bundles facing rearwardly, and means to separate and collect in a suitable container said grain particles. 120 125 130

16. In combination, a grain shocking machine including a shocker basket, and a suitable receiving and conveying mechanism to receive grain bundles and grain particles from the deck of a binder and transfer said bundles to the shocker basket, said mechanism including a suitable grain-tight receptacle, an upright member to deflect successive bundles of grain into the receptacle, means in said receptacle to reverse the position of the bundles so that the butts face rearwardly, said means conveying the bundles upwardly to a delivery pan adjacent the shocker basket, and means to collect said grain particles in a suitable container.

17. In grain shocking apparatus, in combination, a grain-tight metal receptacle adapted to receive grain bundles and grain particles from a binder deck, said receptacle having conveyors to turn the bundles and convey them up a relatively steep incline to the top of the shocker basket, one of said conveyors comprising an endless belt disposed adjacent the bottom of the receptacle and adapted to overlap the rearward end of an upwardly inclined conveyor, whereby the loose grain particles may be carried from the bottom of the receptacle to the upwardly inclined conveyor, and means carried by said upwardly inclined conveyor to convey said grain particles upwardly and deposit them in a suitable container.

In testimony whereof I affix my signature.
GEORGE INNES.
